UNITED STATES PATENT OFFICE

MARGARET HERMANNS, OF MERRICK, NEW YORK

FASTENER FOR SHOULDER STRAPS

Application filed April 8, 1931. Serial No. 528,562.

The present invention relates to improvements in shoulder strap fasteners.

It is well known that much annoyance is experienced by women in holding shoulder straps or ribbons of lingerie in place over the wearer's shoulder. To remove this difficulty various devices have been suggested which to my knowledge and in my experience are objectionable for the reason that they must be and are permanently attached to the over garment. Hence, first, each garment to be worn by the user must be provided with such fasteners and secondly, when the garment is sent to be cleaned the fasteners may be torn off and that will necessitate the attachment of new ones, apart from the fact that when the fasteners are torn off they may also tear the garment.

The object of my invention is to provide a fastener which can conveniently and readily be removably attached to any garment worn by the user in the position where it may be slipped or looped around the different shoulder straps or ribbons of the lingerie and closed so as to hold the latter from sliding down on the arms. Such fasteners can be removed whenever the garment is sent for cleaning or applied to any new garment.

My invention will be more fully understood by reference to the accompanying drawings which forms part of this specification and in which similar reference characters denote corresponding parts.

Fig. 1 illustrates the application of my device to secure shoulder straps in place;

Fig. 2 is a top plan view of my device unfolded;

Fig. 3 illustrates in perspective the attachment of my device to a garment;

Fig. 4 is a sectional view of my device illustrating the relative position of the garment and shoulder straps when my device is employed.

Fig. 5 is a top plan view similar to Fig. 2 of a modified form of my device;

Fig. 6 illustrates the method of attachment of my modified device to a garment; and

Fig. 7 is a side elevation partially in section, of said modification.

Referring to the drawings, 10 denotes a strip of flexible material such as expandible rubberized fabric, rubber bands or any kind of ribbon. The ends of said strip are provided with loops 11 and 12 which may be formed by folding the ends of said strip over upon themselves and fastening them to the band body by sewing or the like. Other means of forming the loops may be employed. A fastening member which may comprise a safety pin 13 is provided whose catch leg 13' is adapted to bear loop 11. The loop 12 is adapted to be removably mountable on the pinning leg 13² of said pin.

In use the strip is folded as at 10' and one part slipped over and the other under the shoulder strap or straps 14. The pinning leg 13² of the pin 13 is then passed through the loop 12 and then pinned to the shoulder portion *s* of the garment *g* and then the pin is closed.

It is to be noted that the strip is so fastened on the garment as to form a transversely extending loop in which said shoulder strap or straps 14 are engaged. The width of the loop is so admeasured as to permit sufficient free play of the shoulder strap or straps to prevent tearing and enable the straps to slide longitudinally through said loop.

To prevent contact between the pin and the wearer's body and also to cover the pin top as much as possible so as to prevent it from injuring the garment, I provide the construction shown in Figs. 5-7. Here 16 denotes a strip of material similar to the strip 10. One end of said strip is provided with a loop 17 similar to the loops 11 12 in the first described construction. The other end of said strip is formed with or has attached thereto an enlargement or pad 18 of the same or other suitable material which has laterally extending wings 18'. The catch leg 13' of the safety pin 13 is adapted to be permanently attached to said enlargement as at 19 by sewing or in any other way.

Suitably attached to the strip 16 near the loop 17 is a lateral strip 20 which extends on each side of the strip 16.

In use the strip 16 is folded as at 16' and

one part slipped over and the other under the shoulder strap or straps 14. The pinning leg 13² of the pin 13 is then passed through the loop 17 and then pinned to the shoulder portion ⁵ of the garment ^g and then the pin 13² is closed. When the strip 16 is so fastened to the garment it forms a transversely extending loop in which the shoulder strap or straps 14 are engaged. The width ¹⁰ of the loop as in the first construction is so admeasured as to permit sufficient free play for the shoulder straps.

The enlargement 18 is adapted to lie under the pin 13 and prevent contact of the latter with the wearer's skin while the lateral strip ¹⁵ 20 is adapted to lie over the greater portion of the upper part of the pin and prevent the catch 13² or other parts of the pin from catching in the garment and injuring the same. ²⁰ To this end the strip 20 is so mounted that the loop 17 only projects sufficiently therefrom to permit easy pinning of the garment. The enlargement or pad 18 may be in form of a cushion or the like to prevent pressing on ²⁵ the wearer's skin. The strip 29 may be likewise constructed.

The pin 13 shown is not the only type which can be employed. Any type of pinning arrangement can be used which will have a pinning member that may be engaged by a catch means after being pinned through the garment.

It is obvious that my invention may be modified in many ways without departing from the spirit thereof and I do not wish to be limited to the details shown and described.

What I claim is:—

1. As an article of manufacture, a fastener for shoulder straps on women's garments comprising a flexible band foldable upon itself to be looped around said straps, pinning means carried by one end of said band, means on the other end of said band for engaging said pinning means, means for engaging said pinning means after the latter has been pinned through a garment and cushioning means at the end portions of said band.

2. As an article of manufacture, a fastener for shoulder straps on women's garments comprising a flexible band foldable upon itself to be looped around said straps, pinning means carried by one end of said band, loop means on the other end of said band for engaging said pinning means, catch means for engaging said pinning means after the latter has been pinned through a garment and cushioning means at the end portions of said band.

3. As an article of manufacture, a fastener for shoulder straps on women's garments comprising a flexible band foldable upon itself to be looped around said straps, a safety pin adapted to be carried by one end of said band, loop means on the other end of

said band for engaging the pinning leg of said safety pin, said pin adapted to be closed after said pinning leg is pinned through a garment and cushioning means at the end portion of said bands.

In testimony whereof I affix my signature.

MARGARET HERMANNS.
